(57) **CLAIM**

The ornamental design for a stud, as shown and described.

DESCRIPTION

FIG. 1 is a perspective view of a stud showing my new design; FIG. 2 is a side view thereof; FIG. 3 is a front view thereof; FIG. 4 is a rear view thereof; and, FIG. 5 is a cross-sectional view taken along line 5-5 of FIG. 4. The broken lines present in the figures are included for the purpose of illustrating portions of the article that form no part of the claimed design.
